BUILDING CONSTRUCTION

Anders C. Olsen, Gwynedd, Pa.

Application January 13, 1940, Serial No. 313,778

5 Claims. (Cl. 72—46)

This invention relates to an improved method and means for forming a wall construction, particularly with respect to partition systems, which is adapted for use in buildings such as offices and the like, wherein there is a definite need for partition systems which may be readily erected or disassembled for changing office conditions.

This invention is concerned primarily with an improved method and means of installing and retaining wall slabs composed of materials possessing such qualities as fireproofness, sound-proofness. These slabs are applied to the spaced stud members in the partition construction and are affixed to adjacent studs, being retained in place in the wall or partition, by various alternative but non-equivalent methods and means which do not impair the physical or structural characteristics of the slabs or of the wall or partition as a whole.

The principal object of the invention is to provide a novel partition system wherein the erection of the partition or the like wall construction is simplified.

The principal features of the invention are that any two adjacent panels can be readily removed to place a door without disturbing any of the partition members; borrowed lights or transoms may be readily placed in or removed from the partition system, and the partition may be erected with pre-painted panels so that office partitions and the like may be erected over night for occupancy on the following day.

Another object of the invention is to provide a novel partition system adapted for interchanging office space from larger to smaller units and vice versa, and incorporating certain features such as ease in laying conduits, flexible cables, and telephone connections.

A further object of the invention is to provide a novel partition system suitable for any height of a partition and particularly adapted either for a dwarf type of partition, or for a ceiling height type of partition, or incorporating such features as having the paneling readily removable and having such characteristics as being fireproof, thermal insulating, and sound-proof.

Another object of the invention is to provide a novel partition system which will withstand the vibration incident to tall building structures such as is inherent to the modern office building.

Another object of the invention is to provide a novel partition system incorporating as a principal feature adjustable studs for leveling purposes, wherein the studs may be readily leveled for applying a flush type removable partition

panel and also adapted for the leveling of the door jambs, borrowed light frames, and the like.

Further objects, features and advantages of the invention will become apparent from the following detailed description of the preferred embodiment of the invention and of the modifications thereof, as illustrated in the accompanying drawings, wherein like reference characters will indicate similar parts and where:

10 Figure 1 is an elevational view illustrating the novel partition system which includes the doors, borrowed lights, transoms, and other known features incorporated in the usual partitions;

15 Figure 2 is a typical vertical section through the flush type partition illustrating the head section and bar section of a transom, a sill section, and a base section;

Figure 45 is a sectional view looking in the direction of the arrows on line 45-45 of Figure 44 illustrating the kerf in a wall slab; and,

Figure 46 is a sectional view illustrating a joint detail between wall slabs.

Referring to Figure 1, there is illustrated the

novel partition or wall construction 50 primarily adapted for interior partition systems but which obviously may be used for exterior wall constructions. The partition 50 comprises the usual door 51 which may be of various constructions, as illustrated at 52, having a transom 53. The partition also comprises the usual borrowed lights 54, baseboard construction 55, and crown molding 56. The partition may also comprise an extension portion 57 when a dwarf type partition is extended to a ceiling height type of partition. As the hardware comprising the doors, borrowed lights and transoms are of standard construction these will not be described in detail as it is obvious that the usual glazed or metal doors may be used and that standard borrowed light sashes and transom frames may be used with this novel construction.

Wall slabs 58 used in this wall construction are of standard width and height preferably 24" in width and 8' in height, thus being adapted for standard dwarf type partition and with the extension stud and sections therefor for ceiling height type of partition. Wall slabs 59 for full ceiling height type of construction may be also used in combination with the standard slabs 58 for dwarf type of partition in conjunction with extension slabs 60. The slabs are preferably supported from studs 61, and the slabs and studs are so complementally formed as to provide that the wall slabs may be readily erected on or detached from the studs when the partitions are rearranged for changing office conditions or when the partitions are being taken down, thus providing that the entire partition system may be salvaged. The further details of the construction of the novel partition system will be described by reference to the remaining figures in the drawings.

In erecting the partition, referring to Figure 2, there is first laid a floor channel 62, the details of which are best illustrated in connection with Figures 30, 38 and 40. A furring strip 63, Figure 2, is secured to the ceiling construction 64 in the usual manner such as by the use of lag screws or toggle bolts. The floor channel is preferably secured to the floor construction in the usual manner such as by the use of lag screws or expansion bolts. A ceiling channel 65, Figures 2, 35 and 38, may then be secured to the furring strip 63 by any of the well-known methods. The studs 61, Figure 38, may then be erected between the floor and ceiling channels 62 and 65 respectively.

After the floor and ceiling channel and studs have been properly erected, aligned and leveled, the wall slabs 58 are then applied. With standard partition construction, the floor and ceiling channels may have suitable projections thereon between which the studs are positioned or, as is indicated in Figure 30, the channels may have slots 66 at standard intervals, whereby the studs may be secured to the floor channel by suitable metal screws or bolts in a well known manner.

Referring to Figures 30 and 38, the studs 61 have thereon struck out portions or prongs 67 for the erection thereon of the slabs 58. The prongs 67 are spaced vertically on the studs 61 at uniform distances, the number being governed by the weight of the slab to be supported. This is best illustrated in Figure 1. The stud 61 is preferably formed from channel-like members 68 having inwardly-turned flanges 69 for stiffening the stud as (it is preferred that) the channel members 68 are preferably formed from thin gauge

sheet steel. In fabricating the stud 61, it is preferred that the channel members 68 thereof shall be spot-welded together, although it is obvious that they may be bolted or otherwise secured.

With studs constructed as described, it is necessary in erecting the partition that the studs shall be leveled and aligned by the use of shims placed between the floor channel and the studs. This alignment is necessary in order that the panels shall be aligned vertically and that they may be readily erected on the supporting prongs 67 of the studs. This is particularly necessary as the respective parts of the stud are not adjustable one with respect to the other. It is however, a particular feature of the invention and one which will be described in detail later to provide a stud member wherein portions of the stud are vertically adjustable relative with respect to each other so that the necessity of leveling of the studs with shims, so that all of the prongs are in alignment, will be unnecessary. In other words, each panel portion may be leveled by itself without being in horizontal alignment with respect to the succeeding panel section.

The wall slabs 58 which in the particular embodiment of the invention are asbestos-cement type of wall slabs have formed therein kerfs 70 for erecting the slabs on their respective studs, as illustrated in Figures 2, 30, 43 and 44. The slabs 58 are very dense and are preferably made and cured under pressure; and, the kerfs 70 are preferably formed therein by sawing, although it is obvious that they may be formed therein by any suitable method. The kerfs or slots, 70 as illustrated in Figures 43 and 44, are preferably cut at an angle of 45° and of sufficient depth to support the slab but not such depth that it will fracture the surface of the slab. The transverse length of the kerf 70 shall be sufficient to take the width of the prong 67, allowing the slab when erected to center on the stud. The kerf should also be of sufficient transverse length, as shown in Figure 30, to allow for lateral adjustment of the slab 58.

In order that an ornamental type of joint shall be formed where the slabs meet at a stud, a ship-lap type of joint 71, as illustrated in Figures 38 and 46, may be used. The contiguous edges of the slabs may be suitably beveled as at 72. Figure 46 illustrates the preferred type of joint construction although a butt type of joint as illustrated in Figures 30 and 35 may be used.

Again referring to Figure 2 which illustrated a typical section through a borrowed light and transom and the partition, the details of the sash construction for the borrowed light and transom will be described. The sash may be of any standard construction, suitably modified as illustrated herein and adapted for this novel type of partition construction. Supporting clips 73 are affixed to studs 61 between which the borrowed light construction is to be erected and for attaching thereto a channel fastener 74 serving to support a borrowed light frame 75. The channel fastener 74 is best illustrated in Figures 13, 14, and 15 and is also adapted for fastening door bucks within the partition system. This construction will be described in detail later on. The channel fastener 74 in connection with the adjustable supporting clips 73 are adapted for different widths of borrowed light frames and door bucks and are readily secured in their adjusted position by any of the well known methods.

The borrowed light frame 75 comprises, as best illustrated in Figure 2, the several preformed

members which are preferably spot-welded together forming a rigid construction. The borrowed light frame comprises a channel shaped frame 76 to which is secured an ornamental frame 77. The ornamental frame 77 is preferably formed as at 78 to constitute a support for a window light 79. The window light 79 is suitably affixed in place by a detachable molding 80. It is obvious that, with the described construction, a simple method is had for glazing a borrowed light frame.

A transom bar section 81 is adapted to be supported by the studs 61 between the borrowed light frame 75 and a transom frame 82. The transom bar section comprises the channel fastener 74 which is similar in construction to that illustrated in Figures 13, 14 and 15 for supporting borrowed light frames and door jambs. It is supported in a similar manner by the clips 73 from the studs 61. Affixed to the channel fastener 74 of the transom bar section 81 are ornamental strips 83. The construction of the transom frame 82 is similar to that of borrowed light frame 75, and although the transom construction, as illustrated in Figure 1, is smaller than the borrowed light construction 54, nevertheless, for the sake of simplicity, like reference characters will indicate similar parts. Having described the borrowed light frame construction 75 in detail, further description of the transom construction is believed unnecessary.

After the borrowed light frames and transom frames, as has been described, have been erected between their supporting studs, as illustrated in Figure 1, it may be necessary to erect an intermediate stud 84, Figure 1, to additionally support the weight of the borrowed light and also the intermediate panels 85. As the construction of stud 84 and the panels 85 are similar to the main studs 61 and wall slabs 58, a detailed description is not necessary as the various elements of the respective parts are similar.

Mounted over channel shaped frame 76, Figure 2, to support the slabs 86, there is a clip member 87 having prongs 67 struck therefrom adapted to engage slots 70, for supporting the slabs 86. A sufficient number of these as illustrated in Figure 1 may be used over the door jambs and borrowed light or transom constructions to support the panels which may be erected above the doors and the like constructions. The clip member 87 may be similar in construction to a base clip member 88 which is best illustrated in Figures 2, 24, 25 and 26. However, the member 87 is preferably formed from a single piece of sheet metal rather than built up as the base clip member 88, and may take the form shown in Figure 27.

Referring to Figures 2, 24, 25 and 26, the base clip member 88 is preferably formed of channel sections 89 having struck out portions 67 engaging the slots 70 in the baseboard slabs 55, illustrated in Figures 1 and 2. The channel members 89 are also notched at 90 to provide a recess, Figure 2, to receive the intermediate slabs 85 or the main wall slabs 58 at the bottom to provide together with the baseboard sections 55 a completely sealed joint between the contiguous panels 55 erected on the clips 88. The channel sections 89 of the clip 88 are suitably spaced by upper and lower spacing bars 91. The spacing bars 91 so space the channels 89 that the clip 88 is adapted to be placed outside of the legs of the floor channel 62 by notching the channel members 89 as at 92. It is, therefore, obvious from the construction of the baseboard clip 88 and the

associated baseboard panels 55 that the panels 55 may be readily detached and attached whenever it is necessary to add telephone lines or further electric wiring in the various rooms and offices which this novel partition construction 5 may form.

In order to complete the erection of the panels, as illustrated in Figure 2, a molding 93 may be placed on the top edges of the wall slabs 58 and small panels such as 86, Figures 1 and 2, in order that the extension slabs 60 may be erected between the top of the dwarf partition and the ceiling. This construction is also illustrated in Figures 35 and 36 wherein the construction of extension studs 94 is shown in detail. The extension slabs 60 or extension portions 57 are erected in grooves 95, Figure 2, formed in the molding 93. The molding 93 is preferably formed so that it resiliently grips the slabs 60 to retain them in place and also is symmetrically formed so that a similar groove 93 resiliently grips the top edges of the slabs forming the dwarf partition construction. The upper edges of the slabs 60 and 57 are held against the depending flanges of the ceiling member 65. The panels are then secured in place by a crown molding construction 96.

So that the partition may be readily erected or dismantled, the crown molding is adapted to be easily attached and detached by having the construction of ornamental molding strip 97 which is formed, as illustrated in Figure 2, so as to snap over securing members 98 which may be in strip form or in short pieces spaced apart to form the equivalent of a continuous strip for attaching the ornamental strip 97. The securing members 98 are preferably secured on opposite edges of the furring strip 63 to which the ceiling channel 65 is erected. It is, therefore, obvious that an ornamental construction or crown molding is provided which finishes the joint between the partition and the ceiling. Figure 35 illustrates a modified construction wherein a crown molding 56 secures the panels 57 in position and also finishes the joint between the partition and the ceiling.

A crown molding construction 99 as also shown in Figure 4 is a modified form of the crown molding construction 96 shown in Figure 2. In this construction shown in Figure 4, an ornamental molding strip 100 snaps over an angular securing member 101. It is apparent that any one of the crown molding constructions is the full equivalent of each of the others, the various types having been described to show that the partition system of this invention is applicable to various forms of crown molding construction. A further modified form comprising a wood molding construction is shown in the molding 56, Figure 36. It is preferred, however, to use the metal form of crown molding where fireproof construction is found necessary, and also as it is adapted to be used over again many times in case the partition is dismantled and erected elsewhere.

In erecting the molding constructions 96 and 99, it is preferred to first position a lip 102 over its complementally formed lip 103 formed on the securing member 98 and then to snap the strip 97 into position over a lip 104 complementary to a lip 105 formed on the ornamental strip 97. Although the design of the crown molding construction 99 illustrated in Figure 4 is different from that shown in Figure 2, nevertheless the principles of construction are similar and therefore like reference characters indicate the similar constructional features of the ornamental 75

strips 100 and of securing members 101 for securing the ornamental strip in position.

A metal clip 106, Figure 2, preferably having a leg, Figure 2, formed thereon for increasing the rigidity of the clip, is formed at its outer ends at 108 substantially in the shape of a T to provide complementally formed securing means for securing the holding strips 93 on opposite faces of the partition. This construction serves to space apart and stiffen the upper portion of the partition at standard height and also to provide a rigid construction when the extension partition members are added to finish the partition from standard height to ceiling height. In securing the molding strips 93, referring to Figure 2, it is preferred to enter the T-shaped portions 108 of the clip 106 at right angles to the position now shown and then turn through an angle of 90°, the resilient portions of the molding strips also serving to secure the clips in their erected positions.

A modified molding construction 109 differing somewhat from that illustrated in Figure 2 is shown in Figure 4, wherein the details of its co-operating metal securing clip 110 and the section through the molding 109 are shown in Figures 17 and 18, and 19, respectively. The clip 110 is formed with a stiffening member 107 similar to that of the clip 106 previously described. Instead of the T-shaped securing means 108, there is, however, an equivalent formed means 111 conforming to the section of the molding 109 so that the moldings 109, Figure 4, are secured in spaced apart relation on opposite faces of the partition assembly. With the molding construction described with reference to Figure 4, the face of the partition is flush and does not have the molding 93 extending from the face of the partition as illustrated in Figure 2.

In the construction illustrated in Figure 4, 40 panel members 60' and 86' are similar to the panels 60 and 86, Figure 2, with the exception, however, that the lower edges and upper edges respectively of the panels 60' and 86' are beveled to conform to the shape of the metal molding 109. With this construction, the face of the partition across the panels 60' and 86' is flush with the exposed surface of the molding 109, providing a surface and molding construction wherein the dust does not collect and which is much easier to clean and decorate the surfaces of the partition.

A clip 112 formed similar to the clip 87 and having prongs 67 struck therefrom for supporting the panels 86' is mounted on a channel shaped frame 113 forming the supporting construction for a modified window sash construction 114. The channel shaped window frame 113 is secured to the stud construction 61 by the usual clips 73, previously described with reference to Figures 13 and 14. An extension stud 60 115 is secured to the clip 112 by means of securing means placed in holes 116.

The modified window sash construction 114 has a U-shaped slot 117 about the inner periphery of the frame in which is mounted a rubber strip 118 for securing the glazing 119 of the window sash.

It is obvious with this type of window light mounting that the windows in the borrowed light construction may be easily mounted in the window sash when the partition is erected and similarly readily removed when the partition is dismantled. It is obvious that the window sash construction illustrated in Figure 4 is an equivalent construction of that illustrated in Figure 2,

and that the constructions may be used interchangeably.

Figure 3 illustrates a novel partition construction adapted to borrowed light constructions wherein the sash is adapted to be pivoted. As this construction is standard, only a brief description of the sash construction will be given. A sash frame construction 120 is adapted to be supported from the stud construction by the usual construction as described with reference to Figure 13 and has mounted in the sash frame a pivoted sash 121. The sash frame 120 is adapted to be mounted in the partition construction through the means of a cross frame construction 122 secured between the studs of the partition and the sash is locked in place by means of a clip construction 123 and the ornamental molding 124 is then applied to finish the space between the sash frame 120 and the lower supporting frame 122.

In order to secure the panels 86 above the window sash 120, a clip 125 having the usual struck-out portion 67 for engaging the kerfs or slots 70 of the panels is mounted above the frame and is substantially U-shaped in section as shown in Figure 3, having a transverse portion 126 which is further stiffened by another U-shaped member 127 welded or otherwise secured thereto. In order to finish off the partition at standard height, moldings 93 are applied at the upper end of the panels 86 and are in turn secured in position by a metal clip similar in form to the clip 106 illustrated in Figure 2, but having a depending leg member 128 which is adapted to be secured to the transverse portion 126 of the clip 125. The clip 128 has the portions adapted for securing the moldings in place similarly formed as the T-shaped end members of the clip 106, and therefore like reference characters have been used to indicate similar parts.

It is apparent that the usual extension slab 60 may be erected in the recesses or grooves 95 provided by the moldings, but in Figure 3 there has been illustrated a crown molding construction 129 for closing over the top of the partition ending at standard height, and the crown molding may be held in place preferably by wedges 130. With this replaceable form of crown molding, it is obvious that if at any time the partition is to be extended to the ceiling, the wedges and crown molding may be removed and the usual extension panels may be added to the partition bringing the partition construction to ceiling height as has been described with reference to Figure 2.

Figure 5 illustrates an horizontal sectional view through a typical window jamb construction. The type of window jamb 131 is a modified form of the sash construction illustrated in Figure 2; and, as it is of a form well known in the art, a detailed description of the sash construction 131 is unnecessary, and therefore only those details will be described which serve to adapt this form of sash to the partition construction of this invention. The stud 61 which is shown in section has mounted thereon and supported by the clips 67 the usual panels 58. Smaller panels 132 for finishing the space between the main panels 58 and the sash are then applied in the usual manner and supported by the usual clips 67 struck out from the stud 61. The panels 132 are preferably beveled as at 133 to form an ornamental joint between the panel 132 and the window sash construction 131. The panel 132 is so formed as to be (usually) mounted on the stud 61 and between 75

the panel 58 and the edge or recess construction 134 in the window jamb 131.

A metal retaining clip 135, as best illustrated in Figure 5, is so formed as to have lugs 136 engaging a formed portion 137 of the window jamb in order to prevent lateral motion of the window jamb with respect to the partition construction and to lock the window sash in place. The clip 135 is supported in an horizontal position preferably by 10 projections 138 struck from the stud 61. It is obvious, therefore, with this construction that, in dismantling the partition, the clips 135 are removed, and then the window sash, after the panels 132 have been removed, may be taken down from 15 the partition construction in order perhaps to replace the window sash by a door or to place additional panels where the window jamb construction had been previously.

Figures 6, 7, 8, and 9 illustrate a typical door jamb construction and modifications thereof and 20 also a sectional view through a typical door head. Referring to Figures 6 and 8, a door jamb 139 is preferably mounted and secured to a stud member 140 similarly formed as one of the channel-like 25 members 68 of the usual stud construction 61 as illustrated in Figure 38. The stud 140 may be welded or otherwise secured to the door jamb 139, but the stud is preferably so mounted as to be detachable from the door jamb 139. The stud 140 has the usual prongs 67 for supporting the 30 panels on the studs. The door jamb 139, Figure 8, is secured in place by a channel member 74 at the upper end thereof as illustrated in Figure 9 in detail. This channel construction 74 is similar to 35 that described with reference to the construction described in Figure 2 and illustrated in detail in Figures 13, 14, and 15. The clip 73 secures the channel 74 to the studs 61 and the upper part of the door jamb construction may be suitably secured to the channel construction 74.

Figure 6 illustrates in section a modified stud construction 141 which is illustrated in detail in the perspective view, Figure 20. This stud construction illustrated in Figure 20 has complementary groove portions 142 struck on each channel-shaped member 143 forming the stud 141. Suitable means may be provided such as slots, which are not shown but which are illustrated in Figure 36 as slots 216 with associated securing bolts, to allow for these members 143 of the stud to slide with respect to each other. With this construction, it is possible that only the stud members supporting their own panels such as panels 144, Figure 6, may have their usual struck-out portion 67 aligned by shimming up the members 143 so that the prongs 67 of this stud member will be in alignment with the prongs 67 of its contiguous stud 140 to provide support for the panel 144. Therefore, with this form of construction, it is not necessary that the prongs 67 across the entire panel construction be in alignment and it is only required that the prongs which support their own particular panel shall be in alignment. The usual panels 58 may then be mounted on the prongs 67 which are adapted to support this panel, as illustrated in Figure 6. The panels 144 may have the edge beveled as at 145, Figure 7, or left square as illustrated in Figure 6. The door jamb 139 is so formed, as at 146 to provide a recess to allow the panel member 144 to fit between its contiguous panel 58 and the door jamb 139.

As illustrated in Figures 8 and 9, panels 147 may be applied over the door head to finish the partition between the door head and the ceiling. As has been disclosed earlier with respect to Figures

1 and 2, the studs 61, or the modified stud construction as illustrated at 141, Figure 6, are preferably erected between the floor channel 62 and the ceiling channel 63 if a ceiling type of partition is required as illustrated in Figure 2; otherwise, panels may be erected such as 86 to form a dwarf type of partition construction as illustrated in Figure 3. The panels 147 may be left square where they meet at the top of the door head or beveled at the edges as illustrated at 145, Figure 7. It is to be understood that the usual reinforcing members 148 may be constructed in the door jamb 139 and in the modified construction 149, Figure 7, for attaching the hinges and other hardware necessary to finish the door construction. It is obvious that the usual door constructions or modifications thereof, as illustrated by the door constructions 51 and 52, Figure 1, may be used to complete the partition construction, or if it is desired, modified arch constructions and doorways may be utilized.

Figure 7 illustrates in cross-section a modified stud construction 150, illustrated in detail in Figures 21 and 22, and also the modified door jamb construction 149. The stud construction 150, Figures 7, 21 and 22, is preferably formed as a closed rectangular stud having complementally formed flanges 151 and 152 to permit relative movement of the members 153 and 154 of the stud 150 with respect to each other in order that the prongs 67 may be aligned with the respective prongs on the studs which support the same panel. It is obvious that the stud construction 150 may be used interchangeably with the studs 61 and 141, previously described, and that it is preferred to shim one or the other of the stud members 153 and 154 depending upon which one is to be aligned so that the supporting prongs on the stud members for supporting the same panel may be in alignment.

The door jamb construction 149, Figure 7, is also so formed that a stud member 155 is adapted to be adjusted relatively with respect to a member 156 forming the principal vertical member of the door jamb 149. The members 155 and 156 also have formed thereon complementally formed flanges 151 and 152 so that the door jamb 149 may be interchanged with the members forming the stud construction 150. The usual panels 58 and 144 may then be erected in place as has been previously described with reference to Figures 6 and 8.

Referring to Figures 21 and 22, the stud construction which has been previously described in detail is the preferred form of stud construction. It is preferred to form this stud at the base with holes 157 to permit conduits and other electrical connections to be fished through the partition. The stud is preferably punched as at 158 in order to secure the clamps 73 for the channel fasteners 74 for door jambs and window transoms. Additional holes 159 may be also punched in the members 153 and 154 for attaching the extension studs thereto or any other prongs which may be necessary to further secure the studs in position. Slots or holes 160 may also be formed in the studs for attaching the studs to the extension studs or to the ceiling channels. It is preferred that the complementally formed flanges 151 and 152 may be so formed that the said members 153 and 154 may be shipped knocked down and then assembled in position at the time when the partition is erected or they may also be assembled at the factory in the finished form of the stud, but it is preferred that these flanges

shall be so formed that they readily slide one with respect to the other to allow the members not only to be assembled but also to be shimmed up when erected in position.

Figure 23 illustrates a modified form of stud construction 161 wherein the stud is modified from that illustrated in Figures 21 and 22 by forming the complementally formed flanges 162 and 163 of the members 164 and 165 forming the stud 161 so that the complementally formed flanges are substantially parallel to the flange portions from which the prongs 67 are formed rather than at right angles as in the stud construction illustrated in Figures 7, 21, and 22. The complementally formed flanges of the stud 161 should also be so formed that the members 164 and 165 slide with respect to each other in order that they may be readily assembled either at the time when the partition is erected or at the factory, and also so that they may be easily shimmed one with respect to the other.

Referring to Figure 10, there is illustrated a preferred form of corner construction which was illustrated in conjunction with window sash constructions 131 of general application and which were previously described with reference to Figure 5. A preferred corner construction 166 is formed from stud members 68, such as described with reference to Figures 2, 35, and 38, and members 167 which may be considered substantially as portions of a stud member 68. A corner structural member 168 is formed to have flanges 169 complementally formed with respect to flanges 170 formed on the members 167. The construction of these flanges 169 and 170 is similar to the construction of the flanges 151 and 152 previously described with reference to the extension stud having members which are adjustable one with respect to the other. The members 167 and 168 which have been so complementally formed are also formed for the same purpose as the adjustable stud 150, that is, so the prongs 67 which have been formed on the various stud members 68, 167, and 168 forming the completed corner stud 166 may be aligned so that the panels 171 and 172 may be readily mounted thereon.

Corner panels 172 and 173 are of opposite hands and are beveled as at 174 so that a corner bead 175 may be mounted at the corner of the corner structural member 168 of the corner stud 166 to complete the corner and prevent breakage of the edge of the panels, and also to provide a rounded corner for ornamentation. The inner corner of the stud 166 also has a corner bead 176 which is preferably welded to the members 68 to complete and strengthen the stud construction. It is also preferred to spot weld or otherwise secure the members 167 to their respective stud members 68. It is therefore obvious that, with this corner construction, the panels 172 and 173 may be easily erected on the prongs for mounting the panels, and that the corner partition construction may be completed by adding a panel 171 and the inner panel members 177 and 178 which are also of opposite hands by erecting these panels on their respective supporting prongs 67. The corner partition may then be completed by adding the panel 171 opposite to the panel 178.

The window sash constructions 131 are also preferably supported from stud members 68 and these also have the usual prongs 67 formed thereon for supporting their contiguous panels. It is preferred that the sash construction 131 shall be secured in position as the partition is erected by bolting or otherwise detachably

mounting the sash constructions 181 on the respective supporting studs 68. It is then obvious that the panels 171, 177, and 178 which have been previously described may be mounted to be supported from the stud members 68 for the sash constructions and also by the stud members 68 forming part of the completed corner stud 166. The panels 177 and 178 are beveled as at 179 to be complementally formed with respect to the corner bead 176.

Figure 11 illustrates in a horizontal sectional view a typical partition intersection. This intersection construction is formed by preferably having the intersection occur at a stud so that the intersecting partition may be rigidly secured thereto. In the intersection illustrated, the preferred stud construction 150 has mounted thereon the usual panel members 58 which have the ship-lap joints 71, and the joint construction is preferably constructed as has been previously described in detail with reference to Figure 46. It is obvious that the panels may be formed either with a ship-lap joint as indicated at 71, or with a butt joint as indicated by panels 58. As the stud 150 has been described in detail with reference to Figures 7, 21, and 22, further description of the stud is believed to be unnecessary. To form an intersection construction of one partition with the partition erected on the stud 150, a stud member 153 is firmly secured to the stud 150 by screws or other suitable securing means. The panels 58 may then be erected on the opposite faces of the stud member 153 in the usual manner. It is therefore apparent that with the novel studs, as illustrated, and members of the studs, that a partition intersection may be readily erected; and it is preferred that this partition intersection shall be erected at a stud, or if necessary, that a stud shall be placed at this intersection in order to add rigidity to the partition construction.

Figure 12 illustrates a typical window head construction for a standard height partition and also illustrates a particular form of crown molding construction which may serve for picture molding. The window head construction is similar to that disclosed in detail with reference to Figure 2 and has been denoted by the reference character 76. A metal clip 180 preferably formed of sheet metal is formed of substantially the same stock as the member 68 of the usual stud construction 61. This metal clip is illustrated in perspective in Figure 27. The clip 180 has a notched portion 181 adapted to overlie a deformed portion 182 which is rolled in the section which serves to stiffen the window sash construction 76. The metal clip 180 has formed on the legs of the clip, as illustrated in Figure 27, prongs 67 which are adapted to support panels 86 which are similar to those described with reference to the construction disclosed in Figure 3.

In order to retain the upper ends of the panels 86 in position and to finish off the partition substantially at what is called a standard height partition construction, a clip 183 is adapted to be positioned over the top of the metal clip 180. This clip 183 preferably comprises a channel-shaped member having down-turned legs contiguous to the legs of the clip 180. Welded or otherwise secured to the member 184 are members 185 and 186 which form resilient securing means for securing a snap-on molding 187. It is preferred to erect the molding by placing a downwardly kerfed portion of the molding 187

so that it overlies the member 186 and then snapping the molding over a resiliently formed portion 188 which not only serves to retain the top portion of the panels 86 in position but also 5 serves to resiliently secure the molding 187 in position. From Figure 12, it is obvious that the clip 183 is so formed that the moldings 187 are positioned away from the rest of the partition construction so that the molding is adapted for 10 mounting of picture frames with the usual picture hooks supported from the molding.

The partition construction may be left at standard height or it may be additionally added to so that the standard partition will be brought to ceiling height. This is accomplished as illustrated in the construction of Figure 12 by securing a furring strip 189 to the clips 183 by any of the well known securing devices and then finishing the partition by erecting between the partition and the ceiling, wall members 190 which may be wall board or the asbestos-cement form of wall slabs previously described.

Since the structures illustrated in Figures 13, 14, 15, 17, 18 and 19, as have been previously described with reference to other constructions previously described in detail, further description of these figures is believed to be unnecessary. Figure 16 illustrates a vertical sectional view of the modified partition system wherein the wall slabs are applied horizontally and are particularly applied to a metal stud construction 191 which may be either stamped in this form or have the web expanded into the form illustrated. In order to retain the walls of the partition contiguous to and in abutting relation to the stud 191, there is utilized the securing clip 110 which has been previously described with reference to Figure 4 and in detail with reference to Figures 17 and 18. As this clip has previously been described in detail further description of the clip is believed to be unnecessary. Wall slabs 192 are preferably formed at their upper and lower edges with a bevel corresponding to the bevel of the molding 109 which is so formed as to be flush with the surface of the wall slabs 192.

The construction of the wall slabs 192 is similar to the construction of the wall slabs 86' and 60' as described with reference to Figure 4 where a standard height partition construction is adapted to be formed into a ceiling height type of partition. It is obvious in erecting a partition as described with respect to Figure 16 that the slabs 192 on opposite sides of the partition must be erected at the same time. Thus if the lower positioned slabs 192 in this figure are first erected, then the clips 110 and the moldings 109 are preferably erected, which provide a support for the slabs 192 which are to be erected thereon. In using a construction of this nature it is preferred that clips 110 may be utilized between the studs wherever necessary to further stiffen and strengthen the partition construction.

Figures 20, 21, 22, 23, 24, 25, 26 and 27, which illustrate various stud constructions and clips for erecting thereon the panels over the sash and door constructions, have been previously described with reference to other figures describing particular partition constructions and these figures therefore need not be further discussed in detail.

Figure 28 is a horizontal sectional view of a modified borrowed light and door jamb construction illustrating the ornamental details. A

door jamb 193 is preferably formed as illustrated in the right hand portion of the figure to receive the usual door construction 194. The door jamb is preferably formed from special rolled members 195 and 196 which may be ornamented in any suitable manner and are preferably spaced apart by U-shaped members 197 in order to add strength and rigidity to the door jamb construction. It is obvious, however, that the U-shaped member 197 may be continuous channel member in this form. Slabs 198 which in this particular construction are preferably asbestos-cement slabs are retained in position on opposite faces of the door jamb construction by a dovetail construction which is formed between the contiguous edges of the slabs 198 and complementary formed portions 199 of the members 195 and 196 forming the steel frame members of the door jamb construction and also part of the sash construction. It is evident that the slabs 198 may be affixed in position at the factory, but they preferably are erected in position as the partition is constructed. Since the member 196 is formed complementary to the wall slab 198 as indicated at 199, the member 196 may be readily secured to the clip 197 which is preferably welded to the jamb member 193; and, as the member 196 is secured in position by means of screws or other suitable securing means 200, the slabs 198 are firmly affixed in their erected position.

To form the opposite sash construction, a specially formed stud 201 is utilized. This stud has features, particularly that of adjusting one part vertically with respect to the other, as has been disclosed with reference to Figures 21, 22, and 23. Therefore, a member 202 of the stud may be considered as being similar to the member 154 of the stud 150 and also its complementary formed member 203 may be considered as being similarly formed as the complementary formed member 153 of the stud 150, with the exception that the member 203 is so rolled as to provide an ornamental sash construction which is similar to the member 196 forming a part of the door jamb and sash construction 193. Obviously then, the stud members 202 and 203 may be relatively adjusted with respect to each other by means of the complementary formed flanges 151 and 152 which have been previously described in detail with reference to Figures 21 and 22.

Ornamental slabs 204 which are similar to the slabs 198 previously described are also readily erected in the dovetail groove formed by the member 203 and the complementary formed member 196. In the same manner, the member 196 secures the slabs 204 in position as the slabs 198 were secured as was described with respect to the door jamb construction 193. After the partition has been erected, it is obvious that glazing 205 for the window sashes may be secured in the sash construction in the usual manner by molding 206.

Figure 29 is a vertical sectional view of a modified partition construction illustrating a typical window sash construction, and it may be considered as the bottom portion of the sash construction illustrated in Figure 28. A sill 207 of the sash construction as illustrated in Figures 28 and 29 is constructed to have an ornamental outline similar to the outline for the members 196 and 201 and is also adapted to mount the glazing 205 and to form a support for the molding 206 which secures the glazing in place. The

molding is also formed with the dovetailed construction 199 which is similar to that which has been disclosed for retaining the ornamental slabs 198 and 204 in position. The sill construction 207 preferably comprises a deep rolled section having leg members 208 integral therewith. Contiguous stud members 61 or the stud and sash construction members 193 and 203 may have the usual prongs 67 engaging the kerfs 70 for supporting the panels 55. The panels 55 at the upper ends thereof adjacent the ornamental portion of the sill construction are complementally beveled to be engaged by the complementally formed sections 199 of the sill. The usual baseboard panels 55 may be erected in the same manner as disclosed with reference to Figure 2. It is preferred in erecting the panels 55 that they are first erected on the stud construction 61 and then the sill 207 placed in position to drop down over the panels 55.

Figures 30, 31, 32, 33, and 34 illustrate in detail baseboard constructions and modifications thereof. Figure 30 has been previously described in detail with reference to the illustrations shown in Figure 2 and modifications thereof of the stud constructions of Figure 30 needs no further description. However, Figure 31 illustrates a sectional view through the partition and particularly illustrates a stud construction having a hole 209 for the usual conduits and electrical connections, which provides for the fishing of conduits and like constructions through the partitions. The figure also illustrates the floor channel construction and method of shimming the floor channel where it is preferred to use U-shaped metal shims 210 for leveling the floor channel 62. It is also preferred that the shims shall be formed to go around the anchor bolts. For securing the channel to the floor, it is preferred that the floor channel shall be punched with $\frac{3}{4}$ inch diameter holes, six inches on centers through which the anchor bolts are placed for securing the floor channel in a level position. Portions 211 may be also formed from the floor channel 62 for spacing the stud members on standard spacings which are preferably 24 inches or multiple or fractional multiples thereof.

Figures 32, 33, and 34 illustrate the preferred form of baseboard clip for securing the baseboard panels in position in the partition. An inverted U-shaped clip 212 is preferably formed from a narrow strip of sheet metal and has transversely formed recesses 213 adapted to receive the lower portions of the main partition panels such as the panel members 58. The lower portion of the clip 212 has hook-shaped members 214 adapted to engage the upwardly extending legs of the floor channel 62, as illustrated in Figure 32 and in the enlarged view, Figure 33. The usual prongs 67 are integrally or otherwise formed on the depending legs of the clip 212 for supporting the baseboard panels 55 in position. The panels 55 and 58 are formed with kerfs 70 or grooves cut at an incline complementally to the prongs 67 for mounting the panels 55 in position. It is apparent from the disclosure with reference to these figures that one may readily attach the baseboard panels 55 in position thus finishing the partition system as it is erected, or when it is necessary to change the conduits or add electrical circuits of any kind, the panels 55 may be readily removed for changing the electrical circuits within the partition system.

Figures 35 and 36 have been previously dis-

cussed with reference to the extension stud construction for changing the partition of standard height to one of ceiling height. Referring to Figures 35, 36, and 37, it is preferred to construct the extension stud 94 of substantially similarly formed channel sections 215, Figure 37, as the channel member 68 of the stud 61. It is preferred, however, that the extension stud members 215 shall slide within the members 68 as illustrated in Figures 35 and 36, and this may be accomplished by deforming the lower end of the members 215 so that they will be complementally formed with respect to the upper end of the stud 61. By so deforming the members, the outer face of the legs of the extension stud 94 will be flush with the face of the studs 61. Slots 216 are preferably formed in the extension stud members, Figure 6, while it is preferred to have holes punched or otherwise formed in the upper ends of the studs 61 complementally formed with respect to the slots 216. The extension studs may then be firmly affixed to the upper ends of the studs 61 by the usual securing means such as bolts, nuts, and washers, as illustrated in Figure 37.

Figure 36 also illustrates a method of securing a molding 93 which has been disclosed in detail with reference to Figure 2 at the upper end of the partition which is of standard height. A modified form of securing clip 217 is adapted for securing the moldings 93 together and for spacing the wall slabs 58 of the partition construction. The moldings 93 are formed, as illustrated in the enlarged section in Figure 2, with recesses 95 for retaining the wall slabs 58 in position. The clip 217 is also preferably formed of two members 218 and 219 which have formed at their outer ends T-shaped members 220 and 221 which are similar to the T-shaped members 108 of the clip 106. These T-shaped members 220 and 221 engage the T-shaped slots of the moldings 93 and as the member 219 is welded or otherwise secured to the member 218 a unitary clip is formed which retains the wall slabs and moldings in place. It is obvious by rotating the clip 217 to a position at right angles to the position illustrated in Figure 36 that the clip may be removed, and the moldings 93 then lifted off of the tops of the panels 58, allowing the panels to be removed one at a time.

To extend the partition to ceiling height, the panels 57 may be erected between the top of the partition of standard height and the ceiling by erecting on the ceiling the usual furring strip 63 and securing thereto the ceiling channels 65 as has been disclosed with reference to Figure 2. The panels 57 may then be erected between the top of the standard height partition and the ceiling by wedging in with wedges 222 the panel members 57 which may be of wall board or other similarly formed materials. The moldings 56 may then be secured in place finishing the joints between the partition and the ceiling.

Figure 38 which has been partly described with reference to previous constructions, will now be described with respect to a modified form of base construction wherein it is preferred to have a metal base board construction 223 rather than the asbestos and cement form of baseboard panel construction as illustrated in Figure 2 and other figures illustrating the same or modified constructions thereof. Referring to Figures 38, 40 and 41, a partition is formed utilizing the previously described floor and ceiling channels 62 and 65 and the stud construction 61. The usual

panels 58 are erected in position by means of the prongs 67 formed on the stud 61 and the complementally formed grooves 70 kerfed in the slabs 58. In order to mount the metal baseboard panels 223 it is preferred to erect clips 224 on the upstanding legs of the floor channels 62 as best illustrated in the perspective view, Figure 38, and in the enlarged sectional view, Figure 41.

The clips 224 are so formed that there is welded or otherwise secured at the upper end of the clip a member 225 adapted to receive the bottom portion of the panel 58. A recess is therefore formed for this purpose between the member 225 and the upper portion of the clip 224. The bottom of the clip 224 has an inverted U-shaped portion 226 which engages the leg portion of the channel member 62. It is preferred to first erect the panels 58 upon the stud construction of the partition system and then place the clip members 24 at intervals along the base portion of the partition system by first inserting the upper end of a clip over the bottom edge of the panel 58 and lifting the clip upwardly allowing the clip then to descend with the inverted U-shaped portion 226 over the leg of the channel 62. It is obvious then that the clip 224 is demountably secured in position and adapted to receive the base panel 223.

The base panel 223 is suitably ornamented by having rolled thereon or suitably formed ornamental beads or similar ornamentation and at the upper end there is also an inverted U-shaped portion 227 adapted to engage a resilient portion 228 of the clip 224. In securing the panel 223 in position, it is preferred to apply the inverted portion 227 over the resilient portion 228 and then snap the bottom portion and its resiliently formed member 229 under another U-shaped portion 230 of the clip 224. It is therefore readily understood from this description that the metal baseboard panels may be readily applied to finish off the partition construction, and also that these panels may be readily moved when the occasion arises for the dismantling of the partition or for the addition to or removal of various electrical circuits which are placed within the baseboard construction of the partition system.

Figure 39 illustrates a modification of the corner construction illustrated and described with reference to Figure 10. In the corner construction illustrated in Figure 39, it is preferred to erect the usual partition system using the stud construction 61 or modified stud construction 141 wherein the panels 58 are erected in place and secured in position with the usual prongs 67 formed on the studs and the complementally formed kerfs 70 in the panels. Where the corner is to be formed it is preferred to use a stud member 231 which has the prongs 67 formed on the legs of the stud member and additional prongs formed on the base of the stud. Panels 232 and 233 may then be erected on the studs 141 and the corner stud 231. It is preferred, however, before the panel 232 is erected that a corner bead 234 shall be mounted along the edge between the base portion of the stud 231 and the leg portion thereof. The finishing corner panel 235 may then be erected in the usual manner as are the regular panel members 58 and those previously described. The partition at right angles to the one previously described is then formed by erecting thereon and securing to the stud 231 a stud construction 68 which is similar to that which has been described with

reference to Figure 10. This stud member 66 has also formed thereon the usual prongs 67 for supporting the panels forming the partition in place.

As illustrated in Figure 46, the joint between the panel 235 and its contiguous panel 236 may have a ship-lap joint construction 71 or it may take the usual form of butt joint construction.

In order to finish the remainder of the corner construction a panel 237 may be erected opposite to the panel 236 and in abutting relationship to the panel 233 so that a tight joint is had at the intersection of the two panels meeting at right angles.

Figures 42, 43, 44, and 45 have been previously described in detail with reference to the various panel constructions which have been described and particularly relate to a construction of the prongs 67 and the complementally formed kerfs or grooves 70 in the panel construction 58 and similarly formed panel members. Although in describing the formation of the prongs 67 on the studs 61 and the like studs construction, it has been described that the prongs are formed on the studs 61, it is obvious that this is a generic use of the term and that by forming of the prongs on the studs 61 this term may also include the equivalent mechanical expedients such as striking the prongs from the original metal of the studs, or it may also include the formation of the prongs separately and spot-welding or otherwise securing the prongs to the legs of the studs.

It will be apparent from the foregoing that the invention provides a number of related but non-equivalent methods and means of attaching relatively thick slabs of wall materials to stud members in the walls of a partition construction. Each of these methods and means is particularly well adapted to use with wall slabs composed primarily of the so-called rigid type of heat insulating material, such as the preferred form in this instance of asbestos fibre and cement panel members, or gypsum block. They may also include slabs of insulation composed of fibrous materials as well as other types of insulating slabs or blocks or ornamental panelling members, such as for example cast or molded materials containing ingredients of good insulating quality or a high percentage of relatively small voids or pockets of entrapped air or inert gas wherein the panels or slabs are so formed that they have relatively high strength and may have incorporated therein the kerfs 70 or other similarly formed structures for erecting the panels onto the studs. The features of the invention are particularly desirable in connection with the use of slabs or blocks of insulating materials since the method and means of attachment provided do not materially decrease the overall efficiency of the insulating material used and eliminate penetrating members of high heat conductivity.

However, the invention is not limited to the use of materials of good heat insulating quality for the wall slabs, since the methods and means provided for attaching the slabs to spaced stud members in the partition or wall construction will also prove advantageous for attaching other types of wall materials where a high degree of insulating efficiency is not essential. Molded or pre-cast slabs of hydraulic cement, natural or synthetic resins, ceramic materials, and the like may be attached to the studs of the partition construction or of any type of construction in the manner and by the means herein provided.

As applied to buildings such as houses, office buildings, factories and the like, any desired form and type of interior and exterior wall materials may be utilized in conjunction with the wall slabs.

5 Although the partition system has been particularly described with reference to interior partition systems and it is preferred that the partitions shall be left either in their natural color or may be suitably decorated by any of the finishing materials well known in the art, nevertheless, if necessary, these wall slabs may have plaster applied thereto as an interior finish and when necessary it may be directly applied to the wall slabs. It is to be understood that expanded metal lath, wire mesh or the like or the usual wall board formed of material known as gypsum wall board or lath may be utilized as a base when desired. Stucco and Kellastone or the like may be applied to the exterior surface of the slabs either without or preferably with a suitable reinforcing mesh. Brick or stone veneer may be applied over the slabs and wood or metal siding of any desired type as well as wood or composition shingles may be employed as an external finish although the panels suitably caulked, as originally erected, may be utilized for an exterior surface when the panels or slabs of asbestos fibre and cement have been suitably sized and painted with a weather resisting surfacing coat. When wood siding, shingles, or panels of wood, metal or composite materials are employed, suitable nailing strips may be anchored to the slabs in any desired manner, such as for example by embedding or anchoring bolts, metal clips, or the like in the asbestos and cement panels or insulating material and attaching the same to the nailing strips. Masonry veneer may also be anchored to the slabs in a similar manner.

It will be also understood that while metal studs have been disclosed for the erection of the asbestos cement form of panels, particularly because of the fireproof character of the asbestos cement panels, nevertheless wood framing may be employed with equal facility in which case 40 the stud may be either square or rectangular or any other suitable shape with the clips or prongs 67 such as has been disclosed in detail with reference to the metal studs for attaching the slabs either nailed or otherwise secured to the equivalent wood stud construction.

It will, of course, be understood that various combinations of the features of the invention, other than the combinations illustrated and described will be obvious to those skilled in the art 55 and are therefore entirely within the scope of the invention as defined by the appended claims. The same applies to various modifications and minor departures from the specific forms of wall slabs as well as the method and means of attaching the wall slabs, herein illustrated and described.

What is claimed is:

1. As an article of manufacture, a stud member fabricated from a channel shaped member, 65 prongs for mounting a panel thereon longitudinally spaced on the legs of the member, and the outer portions of said legs turned inwardly and comprising flanges to strengthen the member and forming complemental interfitting tongue 70 and groove means for adjusting the stud member longitudinally with respect to a similarly formed member to which it may be affixed.

2. A wall construction comprising, in combination, a flooring channel and a ceiling channel, 75 spaced stud members mounted therebetween.

panels of wall material affixed to the stud members, a corner stud member having prongs formed thereon and the corner stud member comprising a plurality of portions connected for vertical adjustment with respect to one another, panels of wall material mounted on the corner stud member and forming inner and outer corners of the wall construction, and inner and outer corner beads mounted on the corner stud member for finishing the corner construction.

3. A wall construction comprising, in combination, spaced stud members, a window sash construction mounted between the studs, panels of wall material mounted contiguous to and above the window sash construction, clip means for supporting the aforesaid panels of wall material, said clip means mounted on the window sash construction, a molding construction at the upper ends of the stud members, said molding construction receiving the upper ends of the panels, clip members for securing together the molding constructions on opposite faces of the wall construction and secured to the aforesaid clip means, and a crown molding construction mounted on the aforesaid wall construction.

4. A wall construction comprising, in combination, a window sash construction comprising a member having an ornamental rolled section, slabs of ornamental material mounted contiguous to the ornamental rolled section and comple-

mentally formed with respect to the ornamental rolled section, a stud member affixed to the member of the window sash construction and adapted for vertical adjustment, contiguous window sash construction secured to the stud member, said window sash construction comprising a member having a similarly formed ornamental rolled section as the first-mentioned member, and said last-mentioned member complementally formed

10 with respect to the slabs of ornamental material, whereby, as the member of the last-mentioned window sash construction is affixed to the adjustable stud member, the slabs of ornamental material are affixed in position on the combined

15 stud and window sash construction.

5. As an article of manufacture, a baseboard clip adapted to support baseboard panels in a wall structure comprising wall panels and a floor channel, said baseboard clip being substantially 20 of inverted U-shape in cross section and having recesses adapted for the reception of edges of the wall panels, prongs formed on the legs of the U-shaped clip adapted to support contiguous mounted baseboard panels, and means formed on the clip complemental to the legs of the floor channels for affixing the baseboard clip to the floor channel whereby the base board panels are supported in the wall structure.
